UNITED STATES PATENT OFFICE

2,613,932

EXERCISING APPARATUS

Frank Manners, New York, N. Y.

Application January 26, 1950, Serial No. 140,567

1 Claim. (Cl. 272—80)

1

This invention relates to new and useful improvements in exercising apparatus for calisthenic and like purposes, and, more particularly, the aim is to provide a novel and valuable such apparatus comprising a skeletal garment to be worn on the body during the exercising period, for effecting such beneficial physical cultural changes as are involved in muscle building, poise and posture correction and perfection, and generally in regard to strengthening and adding tone to the entire body and its various organs.

The new appliance provides what may be called a body harness, the same incorporating a pair of shoulder overlying structures, a pair of ankle stalls, a pair of special stirrups each below one of said stalls, and a pair of endless elongate elastically stretchable structures, these last for convenience hereinbelow termed the cords; said cords each passing through and slidably engaging one of said shoulder structures in a manner such that one depending length of each of said cords extends in an up and down direction at the front of the body and such that another depending length of each of said cords similarly extends at the back of the body; and the arrangement further being such that one of said cords passes through and slidably engages one of said stalls at opposite sides of the latter and also passes through the stirrup below that stall, and the other of said cords passes through and slidably engages the other of said stalls at opposite sides of the latter and also passes through the stirrup below that stall.

Another feature of the invention is the inclusion, in the combination just above summarized, of a breast crossing structure, this slidably engaging the two cords, and a back crossing structure, this also slidably engaging the two cords. As is to be noted from the way these two last referred to structures are characterized, neither is a body girding strap.

A further feature of the invention is the nature of said stirrups, and their operative relationship to the ankle stalls thereabove, in combination with the coupling of each ankle stall and the stirrup therebelow by way of said cords as already mentioned.

A further feature of the invention is the provision of said cords as endless structures as aforesaid, as by knotting together the two ends of an elongate elastically stretchable member; and as in this regard the invention is preferably carried out, each of said cords is comprised of two of said members, with said two members at one of the ends of each knotted together and with

10 said two members at their other ends knotted together.

Still a further feature of the invention is that, with two of such knots at the front of the harness and with the other two thereof at the back of the harness, the former knots are both at and trapped in said breast crossing structure, and the latter knots are both at and trapped in said back crossing structure.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a frontal perspective view of a now favored embodiment of the invention, spread generally as it would be on the body of an exerciser, and with the two cords in unstretched and somewhat slack condition.

Fig. 2 is an enlarged horizontal section, taken substantially on the line 2—2 of Fig. 1.

Fig. 3 is a fragmentary perspective detail view, for showing more clearly one of the two like shoulder structures.

Fig. 4 is a vertical section, taken on the line 4—4 of Fig. 3.

Fig. 5 is an enlarged vertical section, taken on the line 5—5 of Fig. 1 and through one of the two like ankle stalls and the associated one of the two like stirrups.

Fig. 6 shows the parts seen in Fig. 5, but with the ankle stall now spread flat, and looking at the outside thereof.

Fig. 7 is a view like Fig. 1, but showing the harness on a man's body, with the latter quietly standing erect.

Referring now to the drawings in detail, the two like shoulder structures, each as a whole designated 10, are of light-weight construction and made so as to be fairly open to circulation of air therethrough and so as not to be constrictive or uncomfortable. Each structure 10 is comprised of a bottom canvas strip 11 looped back on itself to provide a two-ply base; this base is topped by two shorter outer canvas strips 12, and a middle longer canvas strip 14. To have the central portion of the length of the strip 14 upstand as a handle 15, and to bulge the strips 12 between their ends slightly upward, this last for a purpose to be mentioned in a moment, a plurality of rivets 16, for assembling the elements 11,

12 and 14 to provide the structure 10, are applied as shown.

Referring to the two cords aforesaid, each of these is an elongate elastically stretchable structure passing through and slidably engaging the shoulder structures 10. One of said cords comprises two end to end joined elongate elastically stretchable members 17 and 19 and the other of said cords comprises two end to end joined similar members 18 and 20. As will be noted, referring now to the just above mentioned upward bulges established at the strips 12, the member 17 passes through one structure 10 at said bulges thereof and the member 18 passes through the other structure 10 at said bulges 15 thereof.

Thus at the front of the harness the member 17 has a depending length 17^a, and the member 18 has a depending length 18^a; while at the back of the harness the member 17 has a depending length 17^b, and the member 18 has a depending length 18^b. Thus, also, at the front of the harness, the member 19, complementary to the member 17, has an upcoming length 19^a, and the member 20, complementary to the member 18, has an upcoming length 20^a; while at the back of the harness, the member 19 has an upcoming length 19^b, and the member 20 has an upcoming length 20^b.

The breast crossing structure, this as a whole designated 21, is of quasi-basket-weave construction, for full ventilation and so as not in any way to be constrictive or become uncomfortable from heavy absorption of perspiration.

The back crossing structure, which as a whole is designated 22, is also of quasi-basket-weave construction, and for the reasons just mentioned.

Said structure 21 is comprised of an upper canvas loop 23, a lower canvas loop 24, and a pair of vertically extending cross loops 25; portions of the loops 25 being interwoven or interlaced relative to portions of the loops 23 and 24, and the parts being locked together in this arrangement by a plurality of rivets 26 as illustrated. It will be noted that the rivets 26 are so placed that eye-like openings or localized tunnels are set up in the loops 23 and 24 at opposite sides of the structure 21, and that between each pair of such tunnels at each side of said structure there is established a pocket-like space. Said tunnels of the loop 23 are for slidably receiving the depending lengths 17^a and 18^a of the members 17 and 18 of one of the two cords aforesaid; the said tunnels of the loop 24 are for slidably receiving the upcoming lengths 19^a and 20^a of the members 19 and 20 of the other of said two cords; and said pocket-like spaces are for having trapped therein the knots tied at the meeting ends of the elements 17^a and 19^a and at the meeting ends of the elements 18^a and 20^a.

The back crossing structure 22, like the structure 21, is comprised of canvas loops 27, 28 and 29, corresponding, respectively, to the loops 23, 24 and 25; and, with the rivets 30 corresponding to the rivets 26, four eye-like openings or localized tunnels and two pocket-like spaces are present in said structure 22 as in the structure 21. Said tunnels of the loop 27 are for slidably receiving the depending lengths 17^b and 18^b of the members 17 and 18; the said tunnels of the loop 28 are for slidably receiving the upcoming lengths 19^b and 20^b of the members 19 and 20; and said pocket-like spaces are for having trapped therein the knots tied at the meeting ends of the

elements 17^b and 19^b and at the meeting ends of the elements 18^b and 20^b.

The above referred to knots thus trapped in the structure 21 are designated 31 and 32, while the knots thus trapped in the structure 22 are designated 33 and 34.

Each of the two like ankle stalls is as a whole marked 35. Each such stall is of the wrap-around type and fully openable as shown in Fig. 6.

Below each stall 35 is one of two like stirrups 36; each of those being softly compressible, as by being made of felt, foam rubber or the like, and in the shape of a cylinder having a central bore-like opening extending longitudinally and from end to end thereof.

Each stall 35 incorporates a main strap 37 having extended therefrom a pair of tongues 38 each carrying a line of spaced apertures for selective use relative to a buckle 40. Each buckle is carried by a small strap 39 secured to the outer side of the main strap 37 by a rivet 41. Attached to the main strap 37, adjacent to the attached ends of the small straps 39, there are straps 39^a. The straps 39^a are secured in position by rivets 41^a which are applied so that there is a slight outward bulge of the straps 39^a away from the outer side of the main strap 37.

In regard to one of the ankle stalls 35, such bulgings provide slideways for the upcoming length 19^b of the cord member 19, and in regard to the other of said stalls, such bulgings provide slideways for the upcoming length 20^a of the cord member 20.

Also carried by each stall 35 are two auxiliary small straps 42; these secured in place as shown, and as by way of rivets 43, also to the outside of the main strap 37. These straps 42, it will be noted, are so placed that when the ankle stall is closed and locked closed by the buckle means after being wrapped around an ankle, said straps 42 are at the outer side of the ankle and so much removed from the buckles 40 that these are at the inner side of the ankle. The rivets 43 are so applied to the said small straps 42 that there is a slight outward bulge of each strap 42.

In regard to one of the ankle stalls 35, the two last referred to bulgings provide slideways for the depending length 19^a of the cord member 19, and in regard to the other of said stalls, such bulgings provide slideways for the depending length 20^b of the cord member 20.

As for the substantially bight-like bottom portions of the cord elements 19 and 20, one of these 55 slidably passes through one of the stirrups 36, and the other similarly passes through the other stirrup.

With the new appliance donned as in Figs. 7, and with the cords 17-19 and 18-20 of lengths 60 such that each is then either unstretched or at a selected degree of stretch, any one of a great number of highly beneficial exercises may be performed. With the exerciser standing, or lying prone or supine or at either side, or otherwise 65 basically postured, as, for instance, by being seated on a chair or on the floor, the torso may be swung backward and forward and from side to side, and/or one or both legs may be alternately drawn up and then extended. During these and other exercises, preferably the structure 21 will be placed to extend across the chest and the structure 22 will be placed to extend across the small of the back. Temporarily to increase the initial stretch of the cords, the said structure 22

may be slipped down to cross the buttocks at their region of maximum rearward swell.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:

An exercise appliance having a pair of elastic loops each for extension vertically along the front and back of the human body with diametrically opposite portions of the loop passing over one shoulder and beneath one foot; a pad for each shoulder and including a bulged strap portion slidably receiving one end of said loop, compressible tubular stirrups through which the 20

other end of said loop slidably passes, ankle stalls for each foot, said ankle stalls including bulged straps to slidably receive a loop, said ankle stalls including means for adjustably securing said ankle stalls to the user's ankles, and body bracing web means slidable on said loops securing said loops both on the front and back of the user's body.
